UNITED STATES PATENT OFFICE

HENRY BIRCHALL, OF NEW YORK, N. Y.

MULTIPLE-PLUG RECEPTACLE

Application filed September 14, 1927. Serial No. 219,554.

The device, the subject of this invention is intended as a receptacle for a plurality of plugs.

I am aware that receptacles have been constructed for the reception of one or two attachment plugs, but I am not aware that a receptacle has ever been constructed wherein a greater number of plugs may be inserted and the object of the present invention is to construct and provide a receptacle for the reception of three plugs.

The following is what I consider the best means of carrying out my invention and the accompanying drawing should be referred to for a complete understanding of the specification which follows.

In the drawing:

Fig. 1, is a top, plan view of my device assembled.

Fig. 2, shows in side elevation the interior portion.

Fig. 3, is a top, plan view with one insulating member removed.

Fig. 4, is a sectional view on the line 4—4 in Fig. 3.

Fig. 5, is a perspective view of a bus-bar unit.

Fig. 6, is an enlarged view of a clip.

Fig. 7, is a sectional view taken at right angles to the view shown in Fig. 4.

Fig. 8, is a perspective view of the lower bus bar.

Similar reference numerals indicate like parts in all the figures where they appear.

The face plate 1 of my device may be formed of brass as is the ordinary face plate. This face plate is provided with three oblong openings as shown at 2, 3 and 4, through which projects a portion of an insulating member.

I provide a plurality of screws 5, 6 and 7 for retaining the face plate. Referring to Fig. 2, it will be noted that the insulating portion of my device is made in three sections 8, 9 and 10 and supporting straps 11 passing under the lowermost section and projecting outward from the insulating portion, is provided with screw slots 12 and 13 by means of which the device may be secured to and supported in the box.

The upper insulating member 8 really serves as a cover member for the electrical contacting portions and this member has three upwardly projecting portions 14, 15 and 16 which pass through the oblong openings 2, 3 and 4 of the face plate 1. These upwardly projecting insulating portions are in turn each provided with a pair of oblong perforations as shown at 17, 18 and 19 through which a pin plug may be introduced. The next successively downward member is the member 9 which is also provided with a plurality of perforations extending therethrough and arranged in pairs as shown at 20, 21 and 22 and in each of these perforations I place a contact clip such as is shown at 23 in Figs. 3 and 4 and in increased size in Fig. 6. The insulating member 9 is also provided with recesses 24 and 25, wherein is arranged clips 26 and 27 for the reception of the conductor wires. These clips may be formed integral with the bus bar and the uppermost bus bar 28 shows the general construction of the pair of bus bars which I employ. This uppermost bus bar has a tongue 29 in contact with the clip 27, a tongue 30 upon which the spring contact member 23^a rests, a second tongue receiving the spring contact 23^b and a third tongue 32 receiving the spring clip 23^c. This bus bar may be let into the insulating material from which the member 9 is formed and the general shape and construction of this bus bar is shown in Fig. 5.

The lowermost bus bar indicated by the dotted lines 33 may be flat. It has a tongue 34 projecting into and under the clip 23, a second tongue projecting into and under the clip 23^a and a third tongue projecting under the clip 23^c. An upwardly turned tongue receives or may be formed integral with the wire receiving clip 26. The arrangement of the several spring contact members may be readily noted by referring to the sectional view, Fig. 4 and it will be noted that the slots 18 and 19 through the member 8 align with the open portion of the spring clips 23^a, 23^b, 23^c and 23^d which are exposed to view in Fig. 4.

My device is designed to operate with an ordinary cut-out box and therefore the par-

ticular arrangement of the clips and bus bars is exceedingly important.

The lower plate 10, which is also an insulating member, encloses the lower ends of all of the recesses 20, 21 and 22 and covers the lower bus bar 33. I may provide any suitable means for retaining the portions of my device together. Such a means may be the extension of the sockets which receive the 10 screws 5, 6 and 7, but as such means is common in the art, it will not be necessary to detail or describe such means.

It will be understood that modifications may be made within the scope of the appended claim, without departing from the principle or sacrificing the advantages of the invention, but I prefer the whole as shown and described.

Having carefully and fully described my 20 invention, what I claim and desire to obtain is:—

A device of the character described having a face plate provided with three oblong slots, an insulating member arranged adjacent to said face plate, a second insulating member arranged adjacent to said first insulating member and provided with a plurality of perforations therethrough and a plurality of pairs of spring clips arranged 25 30 35 40 45 each in an independent perforation, a bus bar at the top of said second insulating member and having tongues bent downwardly into said perforations for receiving alternate spring clips and a tongue for receiving a power wire, a second bus bar arranged at the bottom of said second insulating member and provided with tongues for receiving the other alternate spring clips and a tongue for receiving a power wire and a third insulating member arranged under said second insulating member and adapted to shield the current carrying members and a bracket under said third insulating member for supporting the whole in the receptacle box as herein set forth.

Signed at the city, county and State of New York, this 14th day of June, 1927.

HENRY BIRCHALL.
